REFILLABLE ERASER DEVICE

Earl H. Metcalf, Ridgefield Park, N. J.

Application June 30, 1950, Serial No. 171,383

1 Claim. (Cl. 120—36)

1

This invention relates to a refillable eraser device which is particularly useful in erasing one or more letters of typewritten matter without blurring or deleting the adjacent letter or letters.

The general object of the invention is to provide an erasing device which is simple in construction, easily manufactured, and properly supports a long and relatively thin eraser element which may be progressively projected as it is worn down and may be renewed when consumed. As will become apparent, the embodiment of the invention hereinafter described is readily manipulated and refilled with a new eraser element by the user.

The invention will be understood from the following description taken in connection with the accompanying drawing in which the preferred form of the device is shown on an enlarged scale, and in which Fig. 1 is a plan view of the erasing device; Fig. 2 is a side view thereof; Fig. 3 is a sectional plan view on the plane 3—3 of Fig. 2, without the eraser element and with the slide member in its extreme retracted position; Fig. 4 is a plan view similar to Fig. 3 but with the slide member in its extreme extended position; Fig. 5 is a sectional elevation on the plane 5—5 of Fig. 1, showing how the eraser element is gripped and held by the slide member; Fig. 6 is a sectional side elevation, similar to Fig. 5, but with the end of the eraser element largely consumed and with the slide member in its releasing position; and Fig. 7 is an elevation looking at the left end of the erasing device as shown in Fig. 5.

Referring to the drawing, the erasing device therein illustrated has a casing 10, made of sheet-metal or other suitable material, which is rectangular in cross-section and is adapted to house a long and relatively thin eraser element 12 which projects from one end of said casing 10, as shown at 14.

Arranged for limited longitudinal movement in the casing 10 is a slide member which cooperates with the eraser element 12. This slide member comprises a flexible portion 16 which lies adjacent one of the wider walls 17 of the casing 10, and a plunger portion 18 which is slidable in and projects from the end of the casing 10 opposite the end from which the eraser element projects. The plunger 18 of said slide member may be integral with the portion 16, but in the construction shown in the drawing the plunger 18 consists of a block which is secured to the flexible portion 16 of the slide member by means of a rivet 20 which passes through the plunger 18 and through the member 16. At its other end, 50

the flexible portion 16 of the slide member is provided with a toe portion 22 having a serrated end which projects toward and is adapted to engage the eraser element 12 which is located in the space between the member 12 and the opposite wall 24 of said casing 10. Adjacent said toe portion 22, the flexible portion 16 of the slide member is deformed so as to provide a cam portion 26 which cooperates with the edge 28 of the casing wall 17 which is adjacent the portion 16 of the slide member, with the result that when the slide member is in its retracted position (as shown in Fig. 5) the serrated end of said toe portion 22 is forced into gripping engagement with said eraser element 12 which is thus forced against the wall 24 of the casing. Fig. 6 shows said slide member in its extended position in which the pressure of the toe portion 22 on the eraser element 12 is released owing to the position of the cam portion 26 with reference to the edge 28 of the casing.

The slide member is biased toward its retracted position, in which its toe portion 22 grips the eraser element 12, by a compression spring 30 which is located within the casing and cooperates with an abutment carried by the latter and with the plunger 18 forming a part of the slide member. As illustrated in the drawing, said abutment comprises a pin 32 which is carried by the casing 10 and extends across its interior. The compression spring 30 at one end is attached as shown to said pin 32, and at its other end the spring 30 engages the plunger 18 from which a stud 34 projects into the spring thereby retaining the latter during the assembly of the various parts of the device. The pin 32 is shown as provided with a threaded end 35 which enters a threaded hole in a wall of the casing 10, the other end of said pin 32 being provided with a slot 36 which facilitates the rotation of the pin 32 with a screw-driver during assembly. Of course, however, the pin 32 may be secured in the casing 10 by riveting. In order to limit the retracted movement of said slide member 10 under the influence of the spring 30 (when there is no eraser element in the casing), the portion 16 of said slide member is provided with a projecting portion, preferably in the form of an offset lug 37, which is adapted to engage the abutment or pin 32, as shown in Fig. 3.

Figs. 1, 2, 5 and 7 show the eraser device with the eraser element 12 projecting from the casing 10 and ready for use. It will be apparent that the eraser element 12 is then securely held against sliding into the casing during use of the device, by the engagement of the toe portion 22

of the slide member with the eraser element 12 under the influence of the cam portion 26 and the spring 30 which holds the slide member in its retracted position. When the end 14 of the eraser element 12 becomes worn down through use, depression of the plunger 18 will move the slide member and its cam portion 26 into the position shown in Fig. 6, thereby releasing the pressure of the toe portion 22 on the eraser element, whereupon the user with his fingers can pull the eraser element out of the casing a short distance until the eraser element projects beyond the toe 22 sufficiently to permit its satisfactory use. The plunger 18 is then released, and the spring 30 retracts the slide member to the position shown in Fig. 5 in which the toe portion 22 again engages and grips the eraser element 12 and forces it against the wall 24 of the casing. However, in practice it will often be found that during the depression of the plunger 18 and the movement of the slide member (from the position shown in Fig. 5 to the position shown in Fig. 6) the serrated end of the toe 22 will cause the eraser element 12 to slide a short distance out of the casing 10, and when the plunger 18 is released and the slide member retracts under the influence of the spring 30, the toe 22 will slide over the surface of the eraser element 12 until the toe 22 again grips the eraser element 12, in the manner illustrated in Fig. 5. Therefore, in order to extend the eraser element 12 from the casing 10 after the end 14 is worn down, it may only be necessary for the user to depress plunger 18 without using his fingers to pull the eraser element 12 out of the casing.

Since various changes may be made in the details of the construction above described for purposes of illustration, the invention is not to be considered as limited thereto but is to be construed broadly within the purview of the claim.

What is claimed is:

An erasing device comprising a casing rectangular in transverse cross-section and adapted

5 to house a long and relatively thin eraser element which projects from one end of said casing, a slide member having a flexible portion movable longitudinally in said casing adjacent one of the wider walls thereof and projecting from said casing at both ends and providing a space for said eraser element between flexible portions of said slide member and the opposite wall of said casing, said slide member being provided at one 10 end with a block slidable in and projecting from said casing and at the other end with a toe portion projecting toward and adapted to engage said eraser element and having an adjacent cam portion cooperating with the end edge of the wall of said casing which is adjacent the flexible portion of said slide member thereby in the retracted position of said slide member forcing said toe portion into gripping engagement with said eraser element, a pin extending through the 15 narrower walls of said casing and extending across its interior, a compression spring located within said casing and attached at one end to said pin and at its other end surrounding a stud projecting from said block, whereby said spring biases said slide member toward the retracted position in which its toe portion grips said eraser element, said slide member being provided with an offset portion extending into the said space for said eraser element and adapted to engage 20 said pin and limit the extreme retracted movement of said slide member by said spring in the absence of said eraser element.
